DISPLACEMENT TYPE SAMPLER

William J. Leas, Tulsa, Okla., assignor to Standard Oil Development Company, a corporation of Delaware

Application September 16, 1947, Serial No. 774,205

4 Claims. (Cl. 166—1)

1

The present invention is concerned with an improved apparatus for securing a sample of fluid from the bottom of a well. The invention is more particularly concerned with an apparatus and method for taking a sample of a fluid having a relatively high vapor pressure or containing a relatively large amount of a gas. In accordance with the present invention, a sampling device comprising two chambers is used. One chamber is filled with mercury, and at the point of taking the sample, the mercury passes from this chamber to another as the sample enters the chamber from which the mercury is being withdrawn.

In the production of crude oils, it is very desirable and essential that representative samples be secured from the bottom of the well. This is necessary in order to determine the characteristics of the fluid and thus control subsequent drilling and producing operations.

Various procedures have been suggested for taking representative samples. For example, various containers having surface control valves are lowered into the region from which it is desired to secure a sample. Usually the valve is opened and the sample is allowed to enter the container which in many instances is evacuated in order to facilitate the taking of the sample. One disadvantage of this procedure is that the sample of fluid tends to flash, particularly if the fluid has a relatively high vapor pressure or contains a substantial quantity of gaseous constituents.

I have now discovered a process and apparatus by which it is possible to secure a true sample of a highly volatile fluid. My device comprises a displacement type sampler containing two chambers, one of which contains mercury or an equivalent heavy liquid which is immiscible and non-reactive with the fluid being sampled, and which has a greater density than that fluid, while the other chamber is preferably evacuated. I lower my device into the well hole to the desired region at which time a clock operated valve opens the chamber containing the mercury to the fluid to be sampled. After this valve has opened the clock operated valve separating the mercury chamber from the evacuated chamber opens and the pressure of the fluid being sampled causes it to displace the mercury into the evacuated chamber. The rate of displacement of the mercury is limited by an orifice through which the mercury must pass.

My device may be readily understood by reference to the attached drawing illustrating one adaptation of the same. Referring specifically to

2

the drawing, at the surface, chamber A of my displacement type sampler is filled with a heavy liquid, preferably mercury. Clock operated valves 1 and 2 are closed. Chamber B is evacuated and valve 3 likewise closed. I then lower my displacement type sampler into the well hole to the desired depth by means of lowering means 10 attached to cable 9. Lowering means 10 may be in the form of a basket as shown and separable at points 11 and 12 for removal of chambers A and B, supporting lugs 15 being provided to hold the chamber assembly in place in the basket. A port 5 in the uppermost portion of the basket 10 provides fluid access through the basket to chamber A. I adjust the time control on valves 1 and 2 so that I have sufficient time to lower my displacement type sampler to the desired depth before these time control valves operate. Clock operated valves 1 and 2 may be of any suitable design. For example, they may comprise solenoid valves operated by time clocks at the surface, electrical current for the solenoids being fed through suitable conductors carried by the cable supporting lowering means 10. Alternatively the time clocks and the source of electrical current for the solenoids could be placed in a suitable container attached to the device in the bore hole.

After the displacement type sampler has reached the region from which it is desired to secure this sample, time control valve 1 opens, and then time control valve 2 opens. Electric energy for the valves is fed through conductors 17 carried by cable 9. It is not considered necessary to show the operating details of the solenoid valves or of the timing mechanism and electrical circuits feeding the valves since such valves and timing mechanism for opening and closing circuits after predetermined periods of time are well known and can readily be adapted to the present invention by a skilled engineer. The fluid to be sampled passes through port 5 and enters chamber A through valve 1 and displaces mercury from chamber A through the orifice 4 and valve 2 into chamber B. In accordance with the preferred adaptation of my invention, the rate of flow is limited by the size of the orifice 4. This insures that there is no decrease in the pressure of the fluid being sampled and consequently no opportunity for vaporization of same. After a sufficient time has elapsed to enable the flow of mercury into chamber B and to secure a full sample, time operated valves 1 and 2 close. The broad concept of my invention is to employ a sampling device comprising two chambers and to flow a heavy liquid, which is preferably mercury,

from one chamber through a restricting orifice to the other while the sample is entering the chamber from which the mercury or heavy liquid is flowing. This prevents flashing and vaporization of the sample and insures the securing of a very representative sample.

The process of my invention is not to be limited by any theory as to mode of operation, but only in and by the following claims in which it is desired to claim all novelty insofar as the prior art permits.

What is claimed is:

1. Improved process for sampling a fluid in a borehole which comprises bringing said fluid into contact with a first chamber initially filled with a heavy liquid immiscible with said borehole fluid, flowing said heavy liquid by gravity flow from said first chamber into a second evacuated chamber through a restrictive orifice and collecting said borehole fluid sample in said first chamber as a result of the pressure differential created by said flow of heavy liquid from said first chamber into said second chamber.

2. Process as defined by claim 1 wherein said heavy liquid comprises mercury.

3. Improved displacement type sampler for borehole fluids comprising an upper chamber filled with a liquid of greater density than the fluids to be sampled, said chamber having an ex-

terior port, a valve in said port, a lower evacuated chamber, a conduit connecting the upper and lower chambers, said conduit including a restrictive orifice, a second valve in said conduit, and means for opening and closing said valves at selected times.

4. Improved sampler according to claim 3 in which said heavy liquid filling said upper chamber comprises mercury.

WILLIAM J. LEAS.
